Primary Examiner — T. Chase Nelson*Assistant Examiner* — Michelle E Wilson(74) Attorney, Agent, or Firm — Taylor English Duma LLP(57) CLAIM

The ornamental design for a body liner for anal leakage, as shown and described.

DESCRIPTION

This application is related to U.S. application Ser. No. 29/422,461, filed May 21, 2012, which issued as U.S. Pat. No. D720,848 on Jan. 6, 2015, each of which is hereby incorporated by reference in its entirety.

FIG. 1 is a perspective view of a first embodiment of a body liner for anal leakage, in accord with my new design;

FIG. 2 is a top view thereof;

FIG. 3 is a bottom view thereof;

FIG. 4 is a right-side view thereof;

FIG. 5 is a left-side view thereof;

FIG. 6 is a front view thereof; and,

FIG. 7 is a rear view thereof.

The broken lines which define the bounds of the claimed design form no part thereof.
